UNITED STATES PATENT OFFICE.

KRAFT BOOTH, OF PHILADELPHIA, PENNSYLVANIA, ASSIGNOR TO GILLINDER & SONS, INC., OF PHILADELPHIA, PENNSYLVANIA, A CORPORATION OF PENNSYLVANIA.

DESIGN FOR A BOWL, GLOBE, OR PLATE STAND.

51,805.

Specification for Design.

Patented Feb. 26, 1918.

Application filed December 19, 1917. Serial No. 207,986. Term of patent 7 years.

To all whom it may concern:

Be it known that I, KRAFT Booth, a citizen of the United States, residing in the city and county of Philadelphia, State of Pennsylvania, have invented a new, original, and ornamental Design for Bowl, Globe, or Plate Stands, of which the following is a specification, reference being had to the accompanying drawing, forming part thereof.

The figure is a perspective view of a bowl, globe, or plate stand, showing my new design.

I claim:—

The ornamental design for a bowl, globe, or plate stand, as shown.

KRAFT BOOTH.
